UNITED STATES PATENT OFFICE.

RUDOLPH SACHTLEBER, OF BROOKLYN, NEW YORK.

RADIO RECEIVING SYSTEM.

Application filed September 22, 1924. Serial No. 738,967.

My invention relates broadly to radio receiving systems and more particularly to a compact circuit arrangement for radio receiving apparatus and construction of receiving set for reproducing radio broadcast entertainment in the home.

One of the objects of my invention is to provide a circuit arrangement for radio receiving apparatus which will enable the apparatus to be constructed in a compact self-contained unit for convenient operation and reception of radio broadcast entertainment in the home.

Still another object of my invention is to provide an electron tube circuit arrangement for radio receiving apparatus which will maintain a condition of stability without oscillation but secure amplification through the principle of regeneration.

A further object of the invention is to provide a radio frequency collecting system for the broadcast energy consisting of a pair of loops positioned adjacent each other and connected in parallel with the input and output circuits of an electron tube forming part of a radio receiving system and arranged in such manner that oscillations will be prevented while a large increase in the amplitude of the received energy may be secured by regeneration below the point of oscillation.

A still further object of the invention is to provide a construction of radio frequency energy collecting system wherein a pair of loop antennæ is provided with one of the said loops having its turns wound immediately adjacent the turns of the other loop for a portion of its length with the loops connected across the input and output circuits of an electron tube arranged to rectify the incoming signaling energy for delivering the energy to a responsive device.

Other and further objects of the invention reside in the construction and arrangement of parts of the radio frequency energy collecting means and the electron tube circuit arrangements employed at the receiver and will be understood from the specification hereinafter following by reference to the accompanying drawings in which:

Figure 1 is a diagrammatic view showing the arrangement of the radio frequency energy collecting means and the electrical connection thereof in an electron tube circuit at the radio receiver; Fig. 2 shows the ap-

plication of the apparatus of my invention to a complete radio receiving system constructed to operate a loud speaker; Fig. 3 is a side elevation showing the arrangement of the radio frequency energy collecting means which I employ in my radio receiving system; Fig. 4 is an end view of the radio receiving energy collecting means illustrated in Figure 3; and Fig. 5 is an enlarged view showing the arrangement of the pair of radio frequency energy collecting loops which I employ in the radio receiving apparatus.

Heretofore in the art radio receivers have been relatively complicated in construction and difficult for operation by the novice or one unskilled in the electrical art. This has been due largely to the number of controls necessary to operate the receiver and the requirement of providing specially arranged inductances, capacities and resistances for neutralizing inherent tube capacity. By my present invention I provide a compact circuit arrangement wherein the inherent tube capacity is substantially balanced by the provision of parallel connected radio frequency energy collecting loops in the input and output circuits of the tube. The inductances serve to electrically tune the receiving circuit to resonance with the incoming signaling frequency at the same time, that they serve to impress an operating electromotive force upon the tube and maintain the tube circuit in a condition of regeneration without oscillation. The inductances are arranged immediately adjacent each other upon a frame support with one of the inductances extending only throughout a portion of the length of the other of the inductances. By this arrangement of inductances forming the radio frequency energy collecting means I am enabled to secure extremely sensitive and selective operation of the radio receiving apparatus.

Referring more particularly to the drawings reference character 1 designates an electron tube arranged at a receiving station and containing cathode 2, control electrode 3 and anode 4. The cathode 2 is heated by battery 5, the heating current being controlled by rheostat 6 and switch 7. Battery 8 supplies high potential to anode 4 in the output circuit which includes the responsive device 9. The input circuit of the tube 1 across the control electrode 3 and hot cathode 2 is

shunted by the radio frequency energy collecting loop 10 tuned by variable condenser 12. The radio frequency energy collecting loop 14 connected in series with condenser 15 is connected in shunt with the output circuit of electron tube 1 by a connection to cathode 2 and anode 4. The coils 10 and 14 have different lengths one relative to the other and are both spirally wound in the same direction with the turns immediately adjacent each other.

In Fig. 2, I have illustrated the arrangement of my radio receiving system as applied to a compact radio receiving set for the home arranged to operate a loud speaker 16. The tube 1 has its output circuit inductively coupled with the input circuit of an audio frequency amplification system through transformer 17. The audio frequency amplification system comprises tubes 18, 19 and 20 having their input and output circuits coupled through transformers 21 and 22. A negative bias is placed upon the grid of tube 18 by means of battery 23. The grid circuits of tubes 19 and 20 are similarly charged with negative potential from battery 24. The filament temperature for tubes 1, 18, 19 and 20 may be adjusted by individual rheostats 6, 25, 26 and 27, although when once adjusted the filament energy for all of the tubes may be cut on or off by means of switch 7.

The radio frequency energy collecting system is carried upon a frame consisting of a hub 28 having arms 29, 30, 31 and 32 carried thereon and disposed at substantially 90 degrees one with respect to the other. Arm 32 is substantially longer than the other arms and is supported in a vertical position by a base member 33 supporting the frame in a vertical position. Angularly disposed notches 34 are cut in each of the arms and extend at an acute angle with respect to the plane of the arms in opposite angular directions toward the hub 28. That is to say notches are provided in arm 31 as represented at 34 disposed at an angle in the direction of hub 28 while notches 35 are disposed in arm 32 extending in an angular direction opposite to that in which notches 34 extend. Notches 36 and 37 are disposed in arms 30 and 31 respectively and extend in opposite angular directions, that is, in a direction toward each other. The radio frequency energy collecting coils 10 and 14 are carried upon the frame with the turns disposed immediately adjacent each other. The coil 10 starts adjacent the hub 28 at a point 38 and is spirally wound upon the arms 29, 30, 31 and 32 outwardly to a point 39 where the end terminates in a binding post. The inner end 38 of the coil 10 is connected to a binding post 40. The coil 14 also starts at a point 38 adjacent hub 28 and is wound in the same direction as coil 10 terminating at

a point 41. The inner end of the coil 14 connects with binding post 42 on the coil frame while the terminal 41 of coil 14 connects to binding post 43 on the frame. In this manner connections may be taken from the radio frequency energy collecting system from binding posts 39 and 40 to the input circuit of the electron tube system or across grid electrode 3 and cathode 2 while connections may be taken from binding posts 42 and 43 to the output circuit of the electron tube system or across anode 4 and cathode 2.

It will be observed that the values of the inductances may be so selected as to balance the inherent capacity coupling of a tube and that one coil is not oriented with respect to the other coil in the process of selecting and receiving a station. The fact that the radio frequency energy collecting coils are mounted immediately adjacent each other enables the radio receiving set to be compactly constructed and a single control used for tuning. While I have shown a number of individual filament rheostats it will be understood that after these rheostats have been once adjusted that the switch 7 may be used to turn on or cut off the filament heating energy. The inductances being one smaller than the other and arranged to receive the radio frequency energy directly enables the receiving apparatus to be operated with a high degree of efficiency with minimum electrical losses. I avoid the introduction of variometers into the radio frequency energy collecting circuits and secure maximum amplitude of the signal energy in reception by tuning one of the radio frequency energy collecting circuits by variable capacity properly related to the circuits. The pair of energy collecting coils are arranged so that the receiving circuit is in a condition of regenerative amplification below the point of oscillation. The first tube in the receiver also operates as a rectifier simultaneously with its function of amplification.

I may utilize the radio apparatus as herein described in connection with an antenna and ground in order to secure stronger signals, greater amplification, and more volume. In this event I provide an antenna connection at one end of the loop 14 and a ground connection at the opposite end of the loop 14. The coils 10 and 14 then serve as tuning and coupling inductances, giving maximum efficiency over the band of frequencies to be received.

While I have described my invention in a certain particular embodiment I desire that it be understood that modifications may be made by me and that no limitations upon the invention are intended other than those which are imposed by the scope of the appended claim.

What I claim and desire to secure by Let.

ters Patent of the United States is as follows:—

Radio receiving apparatus comprising in combination an electron tube having grid, 5 filament and plate electrodes, an input circuit including said grid and filament electrodes, an output including said plate and filament electrodes, and a pair of radio frequency energy collecting loops superimposed 10 upon each other and connected directly across said input and output circuits, one of said loops having a conductor of greater

length than the conductor forming the other of said loops, said conductors being positioned immediately adjacent each other 15 throughout the length of said shorter conductor and arranged to regeneratively amplify incoming signaling energy below the point of oscillation, said conductors having adjacent ends thereof connected electrostatically. 20

In testimony whereof I affix my signature.

RUDOLPH SACHTLEBER.
